(57) **CLAIM**

The ornamental design for a charger, as shown and described.

DESCRIPTION

FIG. 1 is a front, left and top perspective view of a charger, showing my new design;

FIG. 2 is a front and top perspective view thereof;

FIG. 3 is a rear, left and bottom perspective view thereof;

FIG. 4 is a front view thereof;

FIG. 5 is a rear view thereof;

FIG. 6 is a left side view thereof;

FIG. 7 is a right side view thereof;

FIG. 8 is a top plan view thereof;

FIG. 9 is a bottom plan view thereof;

FIG. 10 is a perspective view thereof, showing the charger in a state of use; and,

FIG. 11 is an enlarged view of portion 11 shown in FIG. 8. The broken lines shown in the drawings illustrate portions of the charger that form no part of the claimed design.

1 Claim, 11 Drawing Sheets
